UNITED STATES PATENT OFFICE.

JACOB SOKOLOV, OF DETROIT, MICHIGAN, ASSIGNOR TO DEFIANCE COMBINATION
AUTO LOCK CORPORATION, OF DETROIT, MICHIGAN, A CORPORATION OF MICH-
IGAN.

LOCK FOR AUTOMOBILES.

1,423,691.

Specification of Letters Patent. Patented July 25, 1922.

Application filed March 27, 1920. Serial No. 369,435.

To all whom it may concern:

Be it known that I, Jacob Sokolov, a citizen of the United States, and resident of Detroit, county of Wayne, and State of Michigan, have invented certain new and useful Improvements in Locks for Automobiles, of which the following is a specification.

My invention relates more particularly to an improved combination lock wherein a plurality of rotatable and depressible keys are employed and adapted, when set according to a predetermined combination, to release the locking bolt by the depression of one or more of the keys. When in locking position, the bolt may be connected to disable some vital part of the automobile mechanism and preferably also lock the steering wheel against rotation.

I am aware that various automobile locks have been devised for disabling and rendering inoperative, vital parts of the operative mechanism of the automobile, but these prior locks employ keys of the ordinary type or operate on the ordinary combination principle. It is desirable in a lock of this character that, when locked, it should be practically impossible for anyone not knowing the combination to so manipulate the combination keys as to be able to learn the combination or release the bolt.

In my improved lock, I have overcome many of the previous objections to locks of this character, and made a lock capable of being set or adjusted through a wide range of combinations and practically impossible of manipulation by one not familiar with the combination so as to release the bolt. Preferably I employ a plurality of depressible keys adapted to cooperate with spring pressed tumblers in a slideable bolt, each of the keys being provided with cooperating members, adapted to limit the depression of the keys the proper amount to release the bolt when the respective keys have been angularly positioned, according to a predetermined combination. Preferably, one or more of the keys is designated as a neutral key and not intended to be depressed when operating the releasing combination, and if depressed is adapted to lock the bolt. Anyone not familiar with the neutral key

and its position, attempting to operate the lock would therefore, find it impossible to release the bolt by depressing the neutral key, even though the remaining keys were at the proper combination.

My improved lock is preferably adapted to be secured to the fixed column surrounding the steering post so that the bolt thereof may cooperate with a spoke of the steering wheel and lock it against rotation, but the bolt may further be provided with a rod or extension which may be connected in the usual or any preferred manner, with the ignition system, the gasoline supply or other vital operating element, so that when the bolt is in locking position, the automobile will be completely disabled.

My improved lock is also so designed that the means for attaching the lock to the fixed column, or other fixed part of the machine will be concealed and rendered inaccessible when the bolt is in place in the housing. Similarly the cover-cap, enclosing the adjustable members for varying the combination, is secured to the housing by screws or other means which are rendered inaccessible by the bolt in place in the housing. These and other important features of my improved lock are adapted to render it safe and secure against the attempts of unauthorized persons to release or remove the lock and thereby secure control of the car.

In the accompanying drawings, I have shown my improved lock as adapted to be attached to the fixed column of the automobile or to the instrument board and have shown several forms or modifications for the combination adjusting members.

Referring to the drawings, Fig. 1 represents one form of my improved lock as attached to the fixed column in position for the bolt to cooperate with the steering wheel, the lock and the attaching clamps being shown in vertical section; Fig. 2 represents a top plan view of the lock attached to the fixed column; Fig. 3 is a transverse cross-section of the fixed column and lock through the upper key of Fig. 1; Fig. 4 is a plan view of the graduated sockets surrounding each of the key stems, the view being taken on the line 4-4 of Fig. 3; Fig. 5 is a sectional development of the circle of sockets

or holes of graduated depth shown in Figs. 1, 4 and 9; Fig. 6 is a sectional view showing one of the keys in depressed position for releasing the bolt; Fig. 7 is a sectional view of a modification; Fig. 8 is a vertical sectional view of another modification; Fig. 9 is a plan view of the socket member taken on the line 9—9 of Fig. 8; Fig. 10 represents my improved lock adapted for attachment to the instrument board of the machine and Fig. 11 is a cross-sectional view of the form shown in Fig. 10.

Referring to the drawings and more particularly to Figs. 1, 2, and 3, the lock is represented as attached to the fixed column 1 of an automobile, the steering wheel being represented partially broken away and in cross-section at 2. My improved lock preferably consists of a housing 3 provided with 20 depending integral clamping member 4 adapted to partially surround the fixed column, as indicated in Fig. 3 of the drawings. A cooperating clamping member 5 is preferably hinged to the member 4 at 6, although 25 obviously any interlocking device may be employed, instead of the hinge. The upper end of the member 5 is provided with a flattened face at 7 adapted to cooperate with a flattened face on the housing or portion 30 thereof representing the extension of the clamping member 4. The members 4 and 5 are preferably secured together and the lock clamped to the fixed column by means of 35 screws entering blind threaded holes in the members 5, the heads of the screws seating in counter-bored holes 9, and adapted to be covered by the locking bolt 10 when the same is in the housing as indicated in Fig. 3 of the drawings. By this construction, it will be 40 seen that the clamping screws for holding the lock in place upon the fixed column are rendered inaccessible after the locking bolt has been placed in the housing. This is desirable in order to prevent removal of the 45 lock by unauthorized persons. The clamping member 5, preferably seats in a flanged socket so that it is impossible to get an instrument between the surfaces 7 to break the clamp, the flange being indicated at 50 in Figs. 2 and 3 of the drawing.

Obviously, it is desirable to prevent displacement of the lock, with reference to its position on the fixed column, and while mere clamping by the clamps 4 and 5 may be 55 sufficient, this may be supplemented by sockets or holes 12 bored in the fixed column, cooperating with dowels or studs 13, projecting inward from the respective clamping members 4 and 5, as indicated in Fig. 3 of the drawings, thereby effectively preventing circumferential or longitudinal displacement of the lock with respect to the fixed column.

The housing 3 of the lock preferably extends longitudinally of the fixed column and

parallel thereto and is bored out, throughout 65 its length, to accommodate the bolt 10, which is slidably mounted therein, and provided at its upper end with a fork 14, adapted, when the bolt is in locking position, to enclose a spoke 15 of the steering wheel 2 and thereby 70 prevent rotation or steering movement of the wheel. The bolt 10 is preferably provided with a plurality of transverse blind or socket holes fitted with pin tumblers 16, each adapted to be thrust outward by a 75 spring 17, the tumblers being preferably equally spaced apart longitudinally of the bolt, substantially as indicated in Fig. 1 of the drawings. The under-side 18 of the bolt is preferably flattened for a short distance and a transverse pin 19 extends through the housing and across the flattened portion 18 of the bolt to prevent rotation of the latter and to limit its longitudinal movement in each direction. It will be noted 80 that I have provided the bolt with six spring pressed tumblers, while the housing 3 is provided with only five cooperating holes into which the tumblers are adapted to enter for locking the bolt. For this arrangement, it 85 will be seen that the bolt may be locked against displacement either in the locking position or in unlocked position. Under some conditions, it may not be desirable to lock the bolt when in idle position, but if it 90 is desired to prevent anyone, not conversant with the combination, from idly or mischievously throwing the bolt to locking position the sixth tumbler as indicated may be employed thus requiring that the combination 95 shall be operated both for locking and for unlocking the automobile.

In the form of lock shown, I preferably employ five spring retracted depressible keys 20, provided with stems 21 entering the five 100 holes in the housing for cooperation with the spring pressed tumblers 16, as indicated more particularly in Fig. 1 of the drawings. Each of the keys is preferably provided with a depending stud or pin 22, located on the 105 flange 23 of each key and adapted to cooperate with a series of holes or sockets 24, arranged in a circle about each key stem 21, as indicated in Figs. 1 and 4 of the drawings. These holes or sockets are preferably of 110 varying depths, the depth increasing from hole to hole, as indicated in the sectional development thereof, shown in Fig. 5 of the drawings. The upper edges or mouths of the holes or sockets 24 are preferably counter-sunk so as to provide a beveled surface or edge for each socket. The studs or pins 22, as indicated in Figs. 1, 3 and 5 of the drawings are preferably threaded into a hole in the flange 23 of the keys 20 and are 115 therefore, adjustable with respect to the cooperating sockets or holes 24. Therefore, by adjusting the studs 22 the holes adapted 120 125

for limiting the depression of the keys to position, the stems and tumblers may be varied and the combination changed.

The upper faces of the keys 20 are preferably provided with a circle of indicating characters 25, corresponding in number to the number of sockets or holes on the housing below the key and an index or starting point provided on the cover cap 27, as will be seen more particularly in Fig. 2 of the drawing. The arrangement is such that by rotating the respective keys to predetermined positions according to the combination known to the operator the respective pins or studs 22 will be brought into position to register when depressed, with corresponding holes or sockets 24, adapted to limit the depression of the keys so that the respective stems 21 thereof will just move 20 the associated tumblers 16 to clear the housing and thereby release the bolt 10.

The several keys are held in proper spaced relation and secured to the housing by the cover cap 27, which is preferably secured to the housing by screws 28, passing through holes in the housing and threaded into blind holes on the under-side of the cap 27, as indicated in Fig. 1 of the drawings. The heads of the screws 28 enter counter-bores 29 which extend transversely of the bolt hole in the housing, the bolt 10 being adapted to conceal the screws and prevent access thereto when the bolt is in place, thereby preventing unauthorized persons from gaining access to the adjustable members and ascertaining or changing the combination. When it is desired, however, to change the combination, the bolt 10 is removed from the housing, the screws 28 withdrawn and the cap 27 removed, after which the adjustable studs or pins 22 may be turned in or out with respect to the key flanges 23, thereby changing the angular positions at which the respective keys are in position for the studs 45 to cooperate with corresponding sockets, adapted to limit the depression of the keys to clear the tumblers and release the bolt. After the combination has been adjustably fixed between the cooperating members, the cover cap 27 may be replaced and secured in position as previously described. The keys, when in place, are adapted to be returned to and held in retracted position by suitable springs 30, thrusting between the housing 55 and the under side of the key, substantially as shown in the drawings.

It will be noted that I have shown five keys in the present form of my device, although the number of keys may be varied as desired. Preferably, I provide that one of the keys, indicated in Fig. 1 as 20^a, shall be so adjusted that the depression thereof will cause the stem 21 of the key to enter the tumbler hole in the bolt 10 and lock the bolt.

In other words, the key 20^a, which I have designated a "neutral key" is not to be depressed when releasing or unlocking the bolt. Only one neutral key is shown, but more may be employed, if desired, and they may be located in any of the five positions 70 so long as the operator, knowing the combination, is aware of the position of the neutral key or keys. This adds to the difficulty of anyone attempting to manipulate the keys and learn the combination, for the 75 chances are that he would have difficulty in determining which one of the keys, if any, is a neutral key and should not be depressed.

While I have shown the several keys as provided with index numbers for properly locating the respective cooperating limiting members, when the keys are rotated, it will be understood that it may be desirable at times to operate the lock in the dark. If it is necessary to do this, it is provided that 80 the operator may locate and count the holes by depressing the respective keys until the stud 22 is in position to contact with the beveled faces of the counter-sunk holes or sockets 24 and by feeling and counting, the 90 operator can determine the angular position of the respective keys according to the known combination. In order to have a starting point for counting in this manner, a pin or stop 31 is preferably inserted between two of the socket holes 24 and projects upward from the housing into the path of the depending stud 22 when the key is partially depressed, as indicated in the drawings, particularly Fig. 4. Therefore, to set 100 the combination in the dark, the operator will first partially depress a key and turn it until the stud 22 thereof comes in contact with the stop pin 31 then by reversing the rotation with the stud 22 rotating over the bevel faces of the holes 24 the proper number of holes can be readily counted off, and the key set in the proper angular position for releasing the corresponding tumbler. 105 When the keys are in the proper angular positions for releasing the bolt and all of them depressed except the neutral key, the corresponding tumblers will be released as indicated in Fig. 6 of the drawings, so that the bolt is free to slide in either direction.

In the form of my improved lock shown in Figs. 1 and 2 of the drawings, I have preferably shown the upper end of the bolt as provided with a fork 14, cooperating with the steering wheel to lock the same against rotation when the bolt is in locking position. I may also provide the bolt with a downwardly extending rod or stem 32 which may be connected in any suitable or preferred manner with valves or switches controlling the gasoline or ignition system of the automobile to disable them in any suitable manner when the bolt is in locking po- 115 120 125

sition. It is thought unnecessary to show any connections of this character for various mechanisms for this purpose are well-known in the art.

5 In Fig. 7 of the drawings, I have indicated an obvious modification in which the key stem 21 is screw threaded and made adjustable instead of the stud 22. Other modifications in the cooperating adjusting members may be made and I have shown another modification in Figs. 8 and 9 of the drawings, in which both the stem 21 and stud 22 of the keys are fixed and non-adjustable and I provide a removable disc 33 in which the socket holes 24 are located, the sockets being of graduated depths as indicated in Fig. 5 of the drawings. The disc 33 is preferably provided with a plurality of radial slots 34, adapted to cooperate 20 with the pin 31^a, which corresponds to the pin 31, hereinbefore referred to. In this modification, (Fig. 8), it will be seen that to change the combination, all that is necessary is to lift the disc 33 and turn it to a new position with respect to the pin 31^a, the position of the proper releasing hole or socket being indicated by a suitable mark or arrow head 35 in Fig. 9 of the drawings. The position of the hole, opposite the arrow 30 35, with respect to the zero position of the pin 31^a, will determine the angular movement required of the corresponding key and give the combination for releasing the bolt.

In Figs. 10 and 11 of the drawings, I have shown a modification, adapted to be secured to the instrument board, the bolt 10^a thereof being adapted to be connected in any suitable or preferred manner with mechanism for disabling the carburetor, 40 cut-off the gasoline supply or break the ignition circuit in any suitable or preferred manner as is well-known in the prior art. The bolt 10^a, in this form of my improvement is preferably square as indicated in Fig. 11 and is provided with spring tumblers 16 and keys 20 corresponding in every respect to and operating in the same manner as in the device as shown and described with respect to Figs. 1, 2 and 3 of the drawings.

45 The corresponding parts are given the same indicating characters and no further description thereof should be required. In this form, (Figs. 10 and 11), the bolt is preferably provided with a handle or knob 36 for moving the bolt up or down, longitudinally of the housing, the latter being provided with a slot 37, as indicated in Fig. 10, through which the knob or handle 36 projects. The corresponding screws 8^a, 50 for securing the housing 3^a to the instrument board 38 are adapted to be concealed and rendered inaccessible when the bolt 10^a is in position in the housing. The screws 8^a pass through the instrument board and

enter blindly into the back-plate 39 thereby 65 securing the lock in position and preventing unauthorized persons from tampering with or removing the same from the machine.

In describing my improved lock, I have shown a few modifications, but obviously, 70 various other modifications in the specific details of construction may be made without departing from the spirit and scope of the invention.

I claim:—

75 1. In a lock, the combination with a bolt provided with a spring pressed tumbler, of a depressible key provided with a stem adapted to cooperate with said tumbler to release the bolt, said key being rotatable about its stem to a predetermined angular position for releasing said bolt when depressed, cooperating members adapted for limiting the depression of the key, and means for adjusting the relation between 85 said cooperating members, whereby the angular position of the key when depressed for releasing said bolt may be varied.

2. In a lock, the combination with a bolt provided with a spring pressed pin tumbler, 90 of a depressible key, a member operable by said key and adapted for cooperation with said tumbler, to move the same to release said bolt when the key is depressed, said key being rotatable to different angular 95 positions, cooperating members adapted to be brought into engagement, when the key is depressed, for limiting the depression of said key, and means for adjusting the relation between said cooperating members, 100 whereby the angular position of the key when depressed for releasing said bolt may be varied.

3. In a lock, the combination with a bolt provided with a plurality of spring pressed 105 pin tumblers, said bolt being slidably mounted in a housing having openings adapted to cooperate with said tumblers to lock the bolt, of a plurality of depressible keys provided with stems entering the tumbler holes in said 110 housing, said keys being rotatable to different angular positions, and cooperating members adapted for engagement between the respective keys and the housing when the keys are depressed for limiting the depression of said keys, the relations between the stems and cooperating members of the respective keys being such that the corresponding tumblers may be moved to release the bolt only at a single predetermined angular position for each key when the keys are depressed to release said bolt. 115

120 4. In a lock, of the character described, the combination of a housing, a slidable bolt extending through said housing and provided with a plurality of spring pressed tumblers adapted to cooperate with holes 125 in the housing for locking the bolt, keys

provided with stems slidably mounted in said holes in the housing for cooperation with said tumblers for releasing the bolt, said keys being rotatably mounted for angular adjustment to predetermined positions for depressing the corresponding tumblers the required amount to release said bolt, and adjustable means for varying the angular releasing positions of the respective keys.

5. In a lock of the character described, the combination of a housing, a bolt slidably mounted therein and provided with a plurality of spring pressed tumblers adapted for cooperation with holes in said housing, a plurality of keys provided with stems entering the tumbler holes in said housing and adapted for cooperation with said tumblers for releasing said bolt by depression of 15 said keys, adjustable members between said keys and the housing for limiting the depression of the keys, said keys being rotatably mounted to vary the angular positions of the respective keys to bring said cooperating 20 members into positions, where, by depression of the keys, they are adapted for simultaneously depressing the corresponding tumblers to release said bolt, a cover cap enclosing said members and through which said 25 keys are adapted to project, said cover being removable when it is desired to adjust said members to change the angular releasing positions of the respective keys and means for securing said cover-cap to the housing, said 30 securing means being inaccessible when said 35 bolt is in the housing.

6. In a lock of the character described, the combination with a bolt provided with tumblers for locking the same, of a plurality 40 of depressible and rotatable keys for cooperation with said tumblers, said keys being adapted to be rotated from fixed starting positions to predetermined angular positions before they are depressed for releasing said 45 bolt, means for locating the starting point from which to measure the angular rotation and means for determining the angular rotation thereof.

7. In a lock of the character described, 50 the combination with a bolt provided with pin tumblers for locking the same, of a plurality of depressible and rotatable keys provided with stems for cooperation with said tumblers, said keys being provided with 55 means whereby they are adapted, when depressed to move said pin tumblers sufficiently to release the bolt only at predetermined angular positions of the respective keys, means for indicating the angular positions 60 of said keys and means whereby the predetermined angular positions of the respective keys for releasing the bolt may be varied to change the combination.

8. In a lock of the character described,

the combination with a bolt provided with 65 spring pressed tumblers for locking the same, of a plurality of depressible and rotatable keys provided with stems for cooperation with said tumblers, means for limiting the rotation of said keys in one direction and 70 from which the angular position of the respective keys may be reckoned and means for determining the relative angular movement of the respective keys when the same are rotated, said means being adapted for 75 determining the angular positions in the dark.

9. In a lock of the character described, the combination with a bolt provided with 80 spring pressed tumblers for locking the same, of a plurality of depressible and rotatable keys provided with stems for cooperation with said tumblers, cooperating members for locating the initial or starting point for measuring the angular rotation of 85 the keys, and cooperating ratchet devices comprising a fixed member and a rotatable member for each key adapted to ratchet, one over the other for counting and determining the angular rotative positions of the 90 respective keys.

10. In a lock of the character described, the combination of a housing, a bolt slidably mounted in said housing, a plurality of 95 spring pressed tumblers in said bolt adapted for cooperation with holes in said housing, a plurality of keys provided with stems entering the holes in said housing for cooperation with said tumblers, said keys being rotatably mounted for adjustment according to predetermined combinations, a plurality of sockets of varying depth located in the housing circumferentially with respect to the stem of each key, a depending stud on each of said keys adapted for cooperation with said sockets to limit the depression of the respective keys, the adjustment between the studs and said sockets being such that only one socket for each key will limit the depression of the respective 105 keys to move the corresponding tumblers so as to release the bolt, and means for changing the relations between the respective studs and sockets so as to vary the angular movement of the keys and thereby change the 110 combination required for releasing said bolt.

11. In a lock of the character described, the combination of a housing adapted to be secured to a fixed part of the automobile, a bolt extending through said housing and 120 slideable therein, provided with a plurality of spring pressed tumblers adapted to enter holes in said housing to lock the bolt, a plurality of depressible keys provided with stems entering the tumbler holes in said 125 housing, said keys being spaced apart longitudinally of said bolt, a cover-cap provided with a plurality of flanged openings through

which said keys project, springs for restoring and holding said keys in their normal positions, means for securing said cover-cap to the housing, said securing means being rendered inaccessible when said bolt is in the housing, cooperating members between the housing and said keys for variably limiting the depression thereof, said keys being angularly adjustable to bring said cooperat-

ing members into positions whereby the respective keys are adapted to operate the tumblers and release the bolt and means, rendered accessible by removing said cover-cap, for changing the relation between said cooperating members for changing the combination. 10 15

JACOB SOKOLOV.
